UNITED STATES PATENT OFFICE.

THOMAS MCGRORY, OF PHILADELPHIA, PENNSYLVANIA.

LOCK WIRE INSULATOR.

SPECIFICATION forming part of Letters Patent No. 293,901, dated February 19, 1884.

Application filed December 14, 1883. (No model.)

To all whom it may concern:

Be it known that I, THOMAS MCGRORY, a citizen of the United States, residing at Philadelphia, in the county of Philadelphia and State of Pennsylvania, have invented certain new and useful Improvements in Lock Wire Insulators, of which the following is a specification, reference being had therein to the accompanying drawings.

10 My invention relates to insulators for telegraph-wires; and the object I have in view is to form an insulator into which the wire may be passed and held securely by the binding of the same, and without wrapping, as is usually the case.

15 In the annexed drawings, making part of this specification, Figure 1 represents a front view, Fig. 2 a side view, and Fig. 3 a longitudinal section, of my improved insulator.

20 In the figures, A represents the body of the insulator, which is made of glass and provided with an opening, D, at its bottom, by means of which it can be secured upon suitable pins upon the cross-bars of telegraph-poles. In 25 one side of this body is formed a V-shaped slot or opening, into which the wire is inserted when to be connected to it.

C represents this opening.

30 B represents a downwardly-inclined projecting ledge. The upper end of this ledge terminates at the lower edge of the mouth of the opening C. The outer surface of the ledge is a tapering oval in shape, and serves to guide the wire to its seat within the slot or opening 35 in the body A. That portion of the body A which forms the lower wall of the opening C

is provided at its inner end with a recess, e, large enough to form a resting-place for the wire.

In the upper wall of the opening C, and running from its outer ends inward and inclining upward, are two grooves, d d, into which the wire is also caught. The wire bears down (when in position) in the recess e and upward in the grooves d d, being bent over the bridge 45 a, thus having two upward bearings and one intermediate downward bearing, all in grooves. It is firmly and securely held in position after once it is forced into the opening C and back to these grooves. The inclined ledge readily 50 guides the wire to the opening C and shapes it, or upon which it may be shaped, to fit said opening.

I am aware that a V-shaped opening is not new in insulators; hence I do not broadly 55 claim such.

Having thus fully described my invention, what I claim as new, and desire to secure by Letters Patent, is—

In an insulator having in one side a V-shaped 60 groove, C, an oval inclined ledge, B, a bridge, a, with recess e at its inner end, and the upwardly-projecting grooves d d at the ends of the opening C, substantially as and for the purpose set forth.

65 In testimony whereof I affix my signature in presence of two witnesses.

THOMAS MCGRORY.
